COMBINATION HANDLE AND HANGER FOR A BROOM OR BRUSH

David W. Anthony, Sudbury, and Richard C. Urie,
Swampscott, Mass., assignors to Stanley Home Products,
Inc., Westfield, Mass.

Filed Apr. 16, 1971, Ser. No. 134,924

Term of patent 14 years

Int. Cl. D4—01

U.S. Cl. D4—4

FIG. 1.

FIG. 2.

FIG. 3.

FIG. 4.

FIG. 5.

FIG. 1 is a front elevational view of a combination handle and hanger for a broom or brush embodying my new design;

FIG. 2 is a side elevational view thereof;

FIG. 3 is a view similar to FIG. 2 with a portion of the outer ring broken away;

FIG. 4 is a top plan view thereof; and

FIG. 5 is a view similar to FIG. 4 with a portion of the outer ring broken away.

We claim:

The ornamental design for a combination handle and hanger for a broom or brush, as shown and described.
